SNARE FOR EGGS AND THE LIKE

Erwin K. Jackle, Sidney, and George Collatz,
Laurens, N.Y.

Application June 27, 1957, Serial No. 46,807

Term of patent 14 years

(Cl. D34—5)

Fig. 1 is a perspective view of a snare for eggs and the like showing my new design;

Fig. 2 is a side elevation thereof.

The handle is shown fragmentarily for convenience of illustration.

We claim:

The ornamental design for a snare for eggs and the like, as shown and described.
